UNITED STATES PATENT OFFICE.

LUCY L. CHURCHILL, OF HINCKLEY, OHIO.

DESIGN FOR A BADGE.

Specification forming part of Design No. **11,180**, dated May 6, 1879; application filed March 21, 1879.
[Term of patent 7 years.]

To all whom it may concern:

Be it known that I, LUCY LOVINA CHURCHILL, of Hinckley, in the county of Medina and State of Ohio, have invented a new and original Design for Freethinker's Badge-Pin, of which the following is a specification.

This design consists of a flat annulus, within which is suspended a representation of the globe. At the top of the annulus is a scroll, on which are the letters U. M. L. From the ends of the scroll laurel branches, with leaves, extend part of the way around the annulus toward each other, but leave a space at the bottom.

The globe pendent from the inner edge of the annulus, and having a free movement, is intended to symbolize that the "world moves." The laurel leaves symbolize the "leaves of learning," while the letters are abbreviations of the words "Universal Mental Liberty."

The whole badge is intended to signify, symbolically, that universal mental liberty is being spread over the world by the leaves of learning, and the badge is intended to be worn by freethinkers and others.

I claim as my invention—

A design for a badge, composed of an annulus encircling a pendent world, and having at the top a scroll with the letters U. M. L. thereon, and laurel branches and leaves extending part way around the annulus toward each other from the ends of the scroll, substantially as described.

LUCY L. CHURCHILL.
